UNITED STATES PATENT OFFICE

CHARLES F. ROBBINS, OF GLENORA, NEW YORK

CARBURETOR

Application filed September 19, 1928. Serial No. 306,796.

This invention relates to carburetors for internal combustion engines or the like, being particularly directed to a thermostatic control of the mixture. More specifically the 5 invention is directed to carburetors of the well-known "Marvel" type, wherein the air valve is located within the mixing chamber of the carburetor, which air valve moves against the pressure of a spring, being connected to a dash-pot which also controls the 10 action of the valve.

In carburetors of this type there is usually a main air inlet, a part of the intake of which is fixed and serves to draw the gasoline up 15 through the main nozzle. The spring-actuated valve before referred to controls only a part of the flow through the main inlet. According to the present invention I provide means for thermostatically controlling such internally arranged air valves whereby the proportions of air and gasoline may be maintained substantially constant at various degrees of outside temperature. According to the invention in its preferred 20 form I introduce a member constructed of thermostatic metal between the air valve and the dash-pot, whereby a given suction will open the air valve to a lesser degree at colder temperatures.

30 Referring to the drawings wherein I have illustrated one of the forms of the well-known forms of Marvel carburetor:

Figure 1 is an elevation partly in vertical section of the carburetor equipped with my 35 improvement.

Fig. 2 is an elevation of the air valve taken approximately on the line 2-2 in Figure 1.

Fig. 3 is a section of the thermostat shown as applied to the air valve.

40 Fig. 4 is a side elevation of the air valve with its dash-pot piston showing a slight modification of Figure 1.

Referring to the drawings, let A indicate the carburetor as a whole, having an air inlet 45 B which is designed to supply substantially all of the air which passes through the carburetor. A' is the throttle, and B' is the usual choke. To the right of the air inlet and close against the wall C is a nozzle D provided with a venturi E, the nozzle being in

communication with the passage F leading from a float chamber G. A substantially constant feed of gasoline takes place from the float chamber, the float operating a needle H which controls the valve opening I leading 55 to the supply, the inlet of which is indicated at J.

The automatic valve control for the air is indicated at K, and is shown as a valve leading to the mixing chamber L, the valve being pivoted on a shaft M and being so proportioned at its lower and rearward end that there is a constant passage around the valve indicated by the arrow and unaffected by the valve. This passage is relied upon for 60 the primary jet, the air flowing up through the venturi and around the jet and serving to maintain a suitable mixture in the mixing chamber L when the engine is idling or the car proceeding at low speed.

An auxiliary jet is employed for higher speeds, said jet being indicated by the reference letter N and leading to a passage which is not shown in the drawing, but which is controlled by the throttle A' in such manner that as the speed of the engine increases greater quantities of gasoline are sucked up through the auxiliary jet. Accompanying this is, of course, an opening of the automatic valve K which opens to a greater or less extent depending upon the suction of the engine.

The air controlling valve K is usually connected directly with a piston O by a link P, the piston O moving in a cylinder Q, piston and cylinder constituting a dash-pot, and there being normally a spring R which loads the valve and tends to move it back to its closed position.

According to the present invention in its 90 preferred form, I interpose between the dash-pot piston O and valve K a thermostat T, and this is best accomplished by mounting the thermostat between the valve and the end of the link P. The thermostat as shown 95 is formed by a loop of flat metal which may be regarded as the usual bimetallic thermostatic metal, the thermostat being reversely arranged, that is to say, so that the two ends of the thermostat tend to approach each other 100

at higher temperatures and to recede from each other at lower temperatures. The result of this construction is that the valve opens wider in warm weather than in cold, 5 and that the variations in opening are substantially proportioned to the variations in temperature.

The thermostat may be connected with the valve and link P in any suitable manner, 10 but preferably it is rigidly attached to the valve by means of rivets U and pivotally attached to the link by bifurcating the thermostat at its ends and forming an eye in each bifurcation, the two legs straddling the link P which is apertured to receive a cotter pin or the like V.

While the thermostat may form the sole connection between the link and the valve, as illustrated in Fig. 4, I prefer to introduce 20 a spring W within the thermostatic loop so as to partially counterbalance the pressure of the spring R, as illustrated in Figures 1 and 3. By this means the thermostat is not subjected to the entire pressure of the spring R, 25 while at the same time it is easily affected by the temperature of the air passing through the carburetor. The spring W may consist of a single piece of wire suitably bent, the two ends of which may be removably 30 connected with the thermostat by passing through holes X formed in the latter.

It will be observed that by locating the thermostat in the manner shown, it lies in the path of the idling or slow speed current 35 of air or mixture as it passes through and around the venturi E. The thermostat is, therefore, admirably located to proportion the air in accordance with the precise temperature of air which is passing into the carburetor.

40 While I have shown and described several forms of the invention, it will be understood that I do not wish to be limited thereby, since various changes may be made therein without departing from the spirit of the invention.

45 What I claim is:

1. A carburetor having an air valve and dash-pot comprising a cylinder and a piston 50 for controlling the movement of said air valve, a compression link directly connected with said piston, and a thermostatic element between said link and said air valve.

2. A carburetor having an air valve and 55 means for opposing its movement, a thermostat connecting said air valve with said means, and a spring arranged to reinforce said thermostat against the effect of said opposing means.

60 3. A carburetor having an air inlet and a primary jet operated by a portion of the air entering said air inlet, an inclined valve controlling the remainder of the air admitted through said air inlet, a dash-pot having a 65 spring for opposing the movement of said

valve, a link connected with said dash-pot body, and a loop-shaped thermostat, one end of which is connected to the valve, and the other end of which is connected to said link, a spring arranged within the loop of the thermostat for opposing its collapse. 70

4. A carburetor having an air inlet, a primary jet operated by a portion of the air entering said air inlet, an auxiliary jet, an inclined valve controlling a portion of the air entering said inlet, and arranged above said auxiliary jet, a dashpot disposed approximately at a right angle to said inclined valve, a spring in said dashpot, a link connected at one end with said dashpot body, and at the other end with said valve, the connection between the valve and link being a thermostat. 75

5. A carburetor having an air valve, means for opposing its movement, and a loop thermostat connecting said air valve with said means, and a spring tending to reinforce said thermostat against the effect of said opposing means. 80

6. A carburetor having an air valve, means for opposing its movement, and a loop thermostat connecting said air valve with said means, and a spring also connecting said air valve with said means, said spring tending to reinforce said thermostat. 85

7. A carburetor having an air valve, resilient means for opposing its movement, a thermostat operating to vary the movement of said air valve, said thermostat being mounted to take the thrust of said resilient means, and a second resilient means arranged to relieve the thermostat of a part of said thrust. 90

8. A carburetor having an air valve, a spring for closing it, a thermostat arranged between said air valve and said spring, and a second spring arranged between said air valve and said spring so as to relieve the thermostat of a portion of the thrust of said first-named spring. 100

In witness whereof, I have hereunto signed my name. 110

CHARLES F. ROBBINS.
